UNITED STATES PATENT OFFICE.

SPEED S. GOODLOE, OF PHILADELPHIA, PENNSYLVANIA.

TOBACCO-PIPE CLEANER.

Application filed September 12, 1925. Serial No. 55,949.

This invention relates to devices for cleaning tobacco pipes and has for its principal object to provide a simple, efficient and comparatively inexpensive attachment which may be expeditiously connected with respect to the supply tube of a tank for supplying compressed air, for tire filling purposes, whereby a motorist when having the tubes of his tires inflated may at the same time 10 utilize such air under pressure for blowing or cleaning out the bowl and stem of his pipe.

A further object is to provide an attachment for use in the manner above described 15 which may be sold over the counter as a new article of manufacture at a nominal charge.

The invention consists of the novel construction hereinafter described and finally 20 claimed.

The nature, characteristic features and scope of the invention will be more fully understood from the following description taken in connection with the accompanying 25 drawings forming part hereof, and in which:

Fig. 1, is a perspective view of an attachment embodying the invention.

Fig. 2, is a central sectional view of the attachment shown in Fig. 1;

Fig. 3, is a diagrammatic view illustrating 30 the manner of blowing out a smoker's pipe by means of compressed air; and

Fig. 4, is a top or plan view of the device.

For the purpose of illustrating my invention 35 I have shown in the accompanying drawings one form thereof which is at present preferred by me, since the same has been found in practice to give satisfactory and reliable results, although it is to be understood that the various instrumentalities of 40 which my invention consists can be variously arranged and organized and that my invention is not limited to the precise arrangement and organization of the instrumentalities as herein shown and described.

The invention, stated in its broadest terms 45 consists of a very simple connecting member, sold as a unitary structure over the counter, which may be conveniently carried in the 50 pocket of motorists and used at a garage or other place (when inflating inner tubes by means of compressed air) to blow or clean out a smoker's pipe.

In the drawings the reference numeral 10 55 designates a frusto-conical member formed preferably of cork, the latter being particu-

larly desirable in view of its adaptability to pipe bowls of different diameters and in view of the fact that it will leave no undesirable odor in the pipe bowl. This cork 60 member 10 has a central bore extending therethrough, through which is extended an externally threaded metal tube 11, the one end of the latter being upset or enlarged as shown at 11'. A washer 12 is applied to 65 the tube 11 to rest upon the enlarged end 11', the outer diameter of the washer being equal to the diameter of the smaller end of the cork member 10. The smaller end of the cork member is fitted against the washer 12 70 which in turn abuts against the enlarged or upset end 11' of the tube 11 so that said cork member is obviously held against movement in one direction by the portion 11'.

The threads of the tube 11 bite against 75 the inner walls of the cork member 10 and assist in retaining the latter in place on said tube, but I also provide a disc-like member 13 having a central threaded opening which 80 engages the threads 11 of the tube and is turned home against the upper face of the cork member 10, as shown in Figure 2 of the drawing, whereby the cork member is securely retained in position on the tube 11. Formed integrally with the disc-like member 85 13 at diametrically opposite points thereon are the opposed finger pieces 14. These finger pieces 14 are bent so as to extend vertically in spaced relation from the cork member and then are bent outwardly upon a 90 curved line to readily accommodate the fingers so that when the cork member is fitted to a pipe bowl 16 the operator may keep the entire device seated within a pipe bowl, particularly when air under pressure, as 95 from a tank 17, is being passed through a pipe bowl and stem. The egress opening 18 of metal tube 11 is preferably of smaller diameter than intake opening 19. The above 100 described device comprises a unitary structure to be sold over the counter as a new article of manufacture and may be readily carried, for instance, in the pocket of a motorist so that when going to a garage to have his inner tubes inflated he may utilize the air supply hose 20 in conjunction with the above described device, to "blow out" or 105 clean his smoking pipe. By inserting the cork member in the bowl of his pipe; holding the same tight by means of the finger 110 grip with one hand; and applying the air supply hose 20 to the exposed end of the

metal tube of the device above described in the same manner that said hose would be applied to the air inlet valve of an inner tube, the operator's pipe may be readily and 5 expeditiously cleared of nicotine and other refuse matter to leave the pipe bowl and stem clean and dry.

It will now be apparent that I have devised a novel and useful construction which 10 embodies the features of advantage enumerated as desirable in the statement of the invention and the above description and while I have in the present instance shown and described the preferred embodiment thereof 15 which has been found in practice to give satisfactory and reliable results, it is to be understood that the same is susceptible of modification in various particulars without departing from the spirit or scope of the invention or sacrificing any of its advantages. 20

Having thus described my invention, what I claim as new and desire to secure by Letters Patent, is:

1. A pipe cleaner comprising a tubular 25 stem having an exterior thread and pro-

vided with an enlargement at one end thereof, a cork engaging the thread of the stem and held thereon against movement longitudinally thereof by the enlargement, a disc member having a thread engaging the thread 30 of the stem, the disc member bearing against one end of the cork and having at opposite side portions fingers disposed along the opposite side of the cork and spaced therefrom.

2. A pipe cleaner comprising a tubular stem, exteriorly threaded and provided at the one end with an outstanding enlargement, a cork engaging the thread and being held against movement in one direction upon the stem by the outstanding enlargement 40 thereof, the cork member having an exterior conical surface, a disc member having a thread engaging the thread of the stem and provided at its opposite side edges with fingers which are longitudinally curved and 45 disposed on opposite sides of said cork member and spaced from the latter.

In testimony whereof, I have hereunto signed my name.

SPEED S. GOODLOE.
